UNITED STATES PATENT OFFICE.

JOSEPH FURNAS MILES, OF PARIS, TEXAS.

AUXILIARY WATER-HEATER AND SMOKE-CONSUMER.

No. 877,444.

Specification of Letters Patent.

Patented Jan. 21, 1908.

Application filed September 27, 1906. Serial No. 336,472.

To all whom it may concern:

Be it known that I, JOSEPH FURNAS MILES, a citizen of the United States, residing at Paris, in the county of Lamar and State of Texas, have invented certain new and useful Improvements in Auxiliary Water-Heaters and Smoke-Consumers; and I do declare the following to be a full, clear, and exact description of the invention, such as will enable others skilled in the art to which it appertains to make and use the same.

This invention relates to improvements in smoke consumers and water heaters for radiators.

The object of the invention is to provide a water heater of this character adapted to be applied to or connected to the stack of a furnace to receive the smoke and gases passing therethrough, whereby said smoke and gases are utilized for heating the return or feed water for the heating system.

With the above and other objects in view, the invention consists of certain novel features of construction, combination and arrangement of parts, as will be hereinafter described and claimed.

In the accompanying drawings:—Figure 1 is a vertical sectional view through my improved smoke consumer and auxiliary water heater, showing the same applied to the smoke stack of a furnace; Fig. 2 is a horizontal sectional view through the same taken on the line 2—2 of Fig. 1; and Fig. 3 is a side elevation partly in section of a modified form and arrangement of the device.

Referring more particularly to Figs. 1 and 2 of the drawings, 1 denotes the furnace, which may be of any character and is here shown as a steam boiler furnace; and 2 denotes the boiler, which may also be of any construction. The furnace 1 is here shown as provided with a smoke box 3 arranged at one end of the boiler and having connected thereto a short stack 4. On the upper end of the stack 4 is arranged the improved smoke consumer and auxiliary water heater 5, said heater being here shown in the form of an upright cylinder closed at its lower end and provided with a removable cover 6 at its upper end. In the cover 6 is formed a centrally-disposed discharge pipe 7, through which the smoke and gases are discharged after passing through the cylinder.

Arranged in the cylinder of the heater 5 is a series of inverted cone-shaped or concave partitions 8 that constitute combined smoke

deflectors and water distributors, the outer edges of which engage the inner walls of the cylinder and are secured thereto in any suitable manner, said cylinder being preferably provided with annular ribs or cleats 9, upon which the outer edges of the partitions 8 are adapted to rest. In the center of each of the partitions 8 is formed an aperture 10. Between each of the partitions 8 is arranged a series of cone-shaped or convex disks 12, that constitute water distributors and which are of somewhat less diameter than the cylinder of the heater and are supported upon and slightly above each of the partitions 8 by means of short lugs 13. The disks 12 are arranged concentrically in the cylinder of the heater with the points of the same projecting slightly in the apertures of the partition 8.

On the top or upper disk 12 is secured a centrally-disposed cup 14, into which is adapted to be discharged the return water from a heating system, said water being conducted to the heater 5 by a return pipe 15. The end of the pipe 15 is adapted to be inserted through the top of the heater in position to discharge the water into the cup 14 as hereinbefore described. The upper edge of the cup is preferably provided with a series of notches 16 by means of which the water overflowing from the cup will be evenly distributed onto the upper disk 12, from which it will run down onto the partition 8 immediately below said disk. The water upon discharging or running onto the partition 8 will pass between the same and the lower edge of the disk 12 and will then run down said partition and through the aperture in the bottom of the same onto the next disk, and so on until the bottom of the heater is reached. The water upon reaching the bottom of the heater is discharged therefrom through a valved discharge pipe 17, by which it is conducted to a suitable strainer 18 arranged in a receiving tank 19, from which it is forced to the radiators or heating pipes by a suitable pump 20.

The water in passing over the disks and partitions in the heater will be acted upon by the smoke and gases passing through the same from the stack of the furnace and will be heated thereby. The cinders or other foreign matter entering the water from the smoke as the same passes through the heater will be removed from the water in passing through the strainer 18, so that the water entering the tank 19 will be pure and free from

all matter which would interfere with the operation of the pump or tend to clog the pipes of the radiators or heating system.

If desired the discharge end of the steam exhaust pipe may be connected with the stack, as shown at 21, thereby utilizing the heat from the steam to assist in heating the water. The end of the stack 4 which enters the lower end of the heater is adapted to project a suitable distance above the bottom of the cylinder to prevent the water from running into the stack and in said projecting end of the stack is preferably arranged a fan 22, which may be operated in any suitable manner and will aid in forcing the smoke and gases through the heater and maintain a draft for the furnace.

In Fig. 3 of the drawings is shown a modified arrangement of the heater, the latter being here shown as applied to the side of a stack and connected thereto at its lower end by an inlet pipe 23, in which is arranged a fan 24, as shown. The upper end of the heater is connected to the stack by a suitable discharge pipe 25, preferably arranged at an angle to facilitate the passage of the smoke from the heater, as will be understood. In the latter form of the device, the stack is preferably provided immediately above the pipe 23 with a damper 26, whereby the smoke and gases from the furnace may be permitted to pass directly through the stack or directed through the pipe 23 to the heater.

The heater shown in Fig. 3 is similar in construction and arrangement to that shown in connection with the first figures of the drawings, except that the fan 24 is arranged below and outside of the heater, as shown.

By providing the heater with a removable cover as hereinbefore described, the upper end of the same may be readily opened and

the partitions 8 and disk 12 removed therefrom for cleaning or other purposes.

At the lower end of the heater is arranged a discharge valve 27 by means of which the same may be drained and cleaned out.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention, as defined by the appended claims.

Having thus described my invention, what I claim as new and desire to secure by Letters-Patent, is:

An auxiliary water heater and smoke consumer comprising a receptacle adapted to be arranged on the upper end of the smoke stack of a furnace, a series of apertured partitions arranged one above the other in said receptacle, a series of disks arranged to alternate with said partitions, a water supply pipe extending into the top of said receptacle, and an overflow vessel arranged in the upper end of the heater to receive the incoming water from said supply pipe and provided with notches in the edge thereof to cause the even distribution of the water overflowing therefrom.

In testimony whereof I have hereunto set my hand in presence of two subscribing witnesses.

JOSEPH FURNAS MILES.
